UNITED STATES PATENT OFFICE.

ROBERT O. MOORHOUSE AND S. LLOYD WIEGAND, OF PHILADELPHIA, PA.;
SAID WIEGAND ASSIGNOR TO SAID MOORHOUSE.

IMPROVEMENT IN BORING-MACHINES.

Specification forming part of Letters Patent No. 141,657, dated August 12, 1873; application filed April 11, 1873.

To all whom it may concern:

Be it known that we, ROBERT O. MOORHOUSE and S. LLOYD WIEGAND, both of the city and county of Philadelphia and State of Pennsylvania, have jointly invented certain new and useful Improvements in Boring-Bars for boring, facing, and turning cylinders; and do hereby declare the following to be a full, clear, and exact description thereof, reference being had to the accompanying drawings and letters of reference marked thereon.

The nature of this invention consists of an improved mechanism for operating the feeding-screw; an improved arrangement for adjusting the frame carrying the propelling-gearing; an improved device for centering the inner end of the bar when applied to a cylinder having a closed or contracted end.

The manner in which the said invention is made and operated may be ascertained by a person skilled in the art from the following detailed description and the drawings annexed and therein referred to.

Figure 1 shows a longitudinal section of a steam-cylinder, marked X X X X, with the boring-bar applied; Fig. 2, an end view of the same; Fig. 3, a section of the boring-head; Fig. 4, a plan of the boring-head; Fig. 5, a section of the bottom-centering device as applied to a closed cylinder-end; Fig. 6, a plan of the centering device; Fig. 7, a section of the driving-gear and frame for attaching it to the cylinder; Fig. 8, a plan of the cross frame or spider used in boring cylinders having both ends open. Figs. 9 and 10, respectively, show plan and section of the feeding-gear.

A represents the boring-bar, having a sleeve, B, accurately fitted so as to slide thereon. The sleeve B has radially-projecting arms, marked B¹, formed on it, and is termed a cutter-head. A radial groove, B², is made in each of the arms B¹, in which grooves the cutting tools B³ are fitted, and are held in place by clamps B⁴ fastened across them by bolts B⁵ screwed into the arms B¹. Through the arms B¹, between the butts of the tools B³ and the sleeve B, are fitted tapering keys B⁶, which, by being moved lengthwise, (preferably by screws B⁷ formed on the ends of the keys B⁶, operated by nuts B⁸), force the cutters outward from the bar A,

so as to bore larger circles, affording a means of adjusting the cutters radially that is specially advantageous in chambering or recessing cylinder-ends. The bar A is fitted so as to turn freely, but without play, in bushings or sleeves A¹, and is prevented from moving lengthwise through said sleeves by collars A², which can be adjusted lengthwise on the bar A and secured in position by set-screws A³. Into a groove formed in the bar A parallel with but eccentric to its axis is placed a screw, C, one end of which, marked C¹, projects beyond the end of the bar A, and is so fitted that it can turn freely but not move lengthwise. A nut, C², fixed securely to the sleeve B, engages in the threads of the screw C, and imparts motion to the cutter-head lengthwise on the bar A when the screw C is rotated. C³ is an internal gear-wheel fitted with a feather, C⁴, on the end C¹ of the screw C, so that when rotated the screw C must rotate with it, and gearing into the pinion C⁵. The proportions of the gear-wheel C³ and pinion C⁵, relatively to each other, to the diameter of the bar A, and to the eccentric position of the screw C, are such that the pinion C⁵ while engaging the teeth of the wheel C³ may be placed with its axis coincident with the axis of the bar A. The pinion C⁵ is fitted so as to turn freely in a bearing, C⁶, fitted on the hub of the wheel C³. A projecting arm of the bearing C⁶ contains a sliding bolt, C⁷, which, by means of a thumb-screw, C⁸, may be held so as to retain one end of the bolt C⁷ in the end of the bar A in a hole drilled for that purpose, so as to maintain the same axial position of the pinion C⁵ and the bar A; or it may be held so that the other end of the bolt C⁷ is confined in a hole in the crank C⁹, by which the pinion C⁵ is turned. When in this position the crank C⁹ operates as though fastened directly on the screw C, and affords a convenient means of turning it rapidly by hand; and when bolted into the bar A, and the handle of the crank C⁹ is held stationary and the bar A rotated, the pinion C⁵ imparts a slow rotative motion through the internal wheel C³ to the screw C, which thus causes a steady and slow progressive movement of the cutter-head B along the bar A. The sleeves A¹ are adjusted centrally by set-screws D' in

the slotted plates D, by which they are secured with screw-bolts and nuts to the cylinder X to be bored. The bar A receives rotary motion from the worm-wheel E, driven by the tangent-screw E¹. The frame E² has an annular T-shaped groove on the side toward the plate D, in which fit the heads of the bolts E³, by means of which it is fastened to the plate D, and can be readily turned so as to place the tangent-screw E¹ in such angular position as to most readily apply the driving-power. F represents a step, into which the extremity of the boring-bar is fitted so as to turn, and has four channeled arms, F¹, in which slide the bars F², which bars are simultaneously pressed radially outward by a nut, F³, screwing on the outside of the step F, and forcing the oblique bars F⁴ against the bars F².

This portion of the apparatus is specially useful in boring cylinders having one end closed or contracted, where the plate D could not conveniently be applied, and centers the

bar in such cases with great facility and accuracy.

We are aware that apparatus for boring cylinders have been made and used embracing several features hereinbefore described, and we do not broadly claim the whole of the same to be new; but

What we claim as our invention, and desire to secure as such by Letters Patent, is—

1. The combination of the internal gear and pinion with the feeding-screw, as shown and described.

2. The frame E², worm-wheel and screw, and plate D combined, as shown and described.

3. The step F with the sliding bars, oblique bars, and nuts for simultaneously expanding the same, as described and shown.

R. O. MOORHOUSE.
S. LLOYD WIEGAND.
